UNITED STATES PATENT OFFICE.

THOMAS K. NAFUS, OF LA SALLE, NEW YORK.

FURNACE-GRAVE.

1,147,536.

Specification of Letters Patent. Patented July 20, 1915.

Application filed April 7, 1914. Serial No. 830,312.

To all whom it may concern:

Be it known that I, THOMAS K. NAFUS, a citizen of the United States, residing in the village of La Salle, county of Niagara, State 5 of New York, have invented a new and useful Furnace-Grate, of which the following is a specification.

My invention relates to improvements in grates, and more particularly to improvements 10 in air-supplying means for furnace grates.

The object of my invention is to provide a grate made up of grate units each of which is provided with improved air-conducting means which produces a more uniform and 15 complete combination of the combustibles and the oxygen supplied; to prevent ashes from falling through the grate when combustion is taking place; to provide means for 20 cutting off or removing ashes when desired; and to provide means for raising or lowering the air-feeding stems (hereafter described) to adapt the same to a thick or thin bed of fuel.

25 Referring to the drawings herewith, Figure 1 is a top plan view of one of my grate units. Fig. 2 is an end elevation. Fig. 3 is a side elevation. Fig. 4 is a plan of a 30 battery of units with their grate-bar connections. Fig. 5 is an end elevation of a group of units, one being shown partly in section.

Each unit consists of a hub portion composed of two cylindrical parts B and C of 35 different diameters but cast integrally as shown,—the diameter of the part B being greater than that of the part C, the axial length of the two portions being equal so that they will fit together, right and left, 40 as clearly shown in Figs. 4 and 5. These hub portions are provided with air chambers E, cylindrical in form, the ends of which chambers are partially closed down into squared openings d, within which the 45 squared portions of the grate-rods H fit. Leading from these air chambers E are air ducts G, which are tapering and which have their smaller orifices upon the cylindrical surfaces of the parts B and C. These ducts, 50 extending radially as shown, serve to admit air from the under side of the grate into the air chambers E and to discharge it into the fuel upon the upper side of the grate. Extending upwardly from the cylindrical portions B are air-feeding stems A, which are 55 tapered externally, preferably, which are

open at their outer ends and which openings connect with the air chambers E by passages or ducts K. These air-feeding stems have perforations in their sides, as shown at G' 60 in Figs. 3 and 5, for the exit of air at points lower than the end orifices. The units thus described are arranged right and left, or alternately reversed axially, as shown in Fig. 4, and are carried by grate-rods H, 65 which have squared portions to fit the square holes d, and which are supported in grate frame i by being journaled therein as shown at J. The right-and-left arrangement of these units is indicated by the reference 70 characters R and L in Figs. 4 and 5. The grate-rods H are secured against axial movement in any desired manner (not shown), and have their outer ends squared (not shown) to receive a shaker. Each of the 75 units has a notch or cut-away portion f in the cylindrical portion B, as clearly shown in Figs. 2 and 5. These notches are so arranged that, when the grate is in the normal position, there are no spaces between the 80 units. But when the units are rocked by turning the grate-rods H to the position shown in broken outline in Fig. 5, these notches make openings between the units through which the ashes may pass down or 85 be cut off in the usual manner.

It will now be seen that the air is drawn or forced in through the radial ducts G having their orifices upon the under sides of the units into the chambers E, and from the 90 chambers E will pass through the ducts G having their orifices in the fire area, and especially will pass through the stems A into the mass of the superposed fuel. And it will also be seen that, when the stems A 95 occupy vertical positions as shown, they will discharge air into a deep or thick bed of fuel; while if these stems be slightly rocked in reverse direction from that shown in broken outline in Fig. 5 they will be 100 adapted to a thinner bed of fuel.

It will be understood that I have described and shown but a single battery of units, and that such battery may be extended or duplicated to any desired extent to 105 form any desired grate area.

I claim:

1. A grate of the type described composed of a plurality of grate units, each unit comprising a body portion made up of two cylindrical parts of different diameters but equal in axial length, having an air cham-

ber and air ducts leading from said chamber to the cylindrical surfaces, an air-feeding stem on each unit capable of projecting upwardly into the fire area and having its 5 air passage connected with said air chamber, and means for revolubly mounting said units on grate bars.

2. A grate of the type described composed of a plurality of grate units, each unit comprising a body portion made up of two cylindrical parts of different diameters but equal in axial length, having an air chamber and air ducts leading from said chamber to the cylindrical surfaces, an air-feeding stem on each unit capable of projecting upwardly into the fire area and having its air passage connected with said air chamber, and means for mounting said units comprising grate-rods having squared portions taking through squared holes in said units and grate frame for supporting said grate-rods.

3. A grate of the type described comprising a plurality of grate units each unit 25 formed of two integral cylindrical bodies of different diameters but of equal axial lengths, whereby the same may be arranged right and left to form a substantially closed grate, said units having internal, cylindrical air chambers closed down at their ends to square openings to fit over the squared portions of 30 grate-rods, air ducts arranged radially to permit ingress and egress of air from said air chambers, an air-feeding stem extending from the cylindrical portion having the greater diameter for feeding air from said air chamber into the bed of fuel, 35

grate frame and grate-rods journaled therein, said bars taking through said squared openings in said units, and notches cut into 40 the sides of said cylindrical portions having the greater diameter whereby, when said units are rocked or partially rotated by rotation of their grate-rods, said notches will form openings in said grate through 45 which ashes may pass.

4. A grate of the type described comprising a plurality of grate units each unit formed of two integral cylindrical bodies of different diameters but of equal axial lengths, whereby the same may be arranged right and left to form a substantially closed grate, said units having internal, cylindrical air chambers closed down at their ends to square 50 openings to fit over the squared portions of 55 grate-rods, air ducts arranged radially to permit ingress and egress of air from said air chambers, an air feeding stem extending from the cylindrical portion having the greater diameter for feeding air from said 60 chamber into the bed of fuel, grate frame and grate-rods journaled therein, said bars taking through said squared openings in said units whereby, when said units are turned slightly in the direction opposite to 65 that which produces openings for the discharge of ashes, the said air-feeding stems are swung from a vertical position to adapt their discharge of air to a thinner bed of fuel upon the grate.

THOMAS K. NAFUS.
